DESIGN FOR A KITCHEN CASE

Oak Landaw, Nappanee, Ind.

Application January 6, 1936, Serial No. 60,446

Term of patent 7 years

To all whom it may concern:—

Be it known that I, Oak Landaw, a citizen of the United States, residing at Nappanee, in the county of Elkhart, State of Indiana, have invented a new, original, and ornamental Design for a Kitchen Case, of which the following is a specification, reference being had to the accompanying drawing forming a part thereof.

I claim:—

The ornamental design for a kitchen case as shown.

OAK LANDAW.
